(57) **CLAIM**

The ornamental design for a light fixture as shown and described.

DESCRIPTION

FIG. 1 is a perspective view of a light fixture;
FIG. 2 is a front view of the light fixture;
FIG. 3 is a right side view of the light fixture;
FIG. 4 is a top plan view of the light fixture;
FIG. 5 is a rear view of the light fixture;
FIG. 6 is a left side view of the light fixture;
FIG. 7 is a bottom plan view of the light fixture;
FIG. 8 is a perspective view of a housing of the light fixture in FIG. 1;

FIG. 9 is a front view of the housing;
FIG. 10 is a right side view of the housing;
FIG. 11 is a top plan view of the housing;
FIG. 12 is a rear view of the housing;
FIG. 13 is a left side view of the housing; and,
FIG. 14 is a bottom plan view of the housing.
The broken lines in the drawings illustrate portions of the light fixture which form no part of the claimed design.
